WATER CLOSET

James A. Tiller, Louisville, Ky., assignor to American
Radiator & Standard Sanitary Corporation, New York,
N.Y., a corporation of Delaware

Filed July 24, 1963, Ser. No. 75,944

Term of patent 14 years

(Cl. D4—5)

Fig. 2.

Fig. 1.

Fig. 3.

The rear of the tank is flat and plain.

I claim:

The ornamental design for a water closet, substantially as shown and described.
